UNITED STATES PATENT OFFICE.

CHARLES P. MASSARD, OF ST. JOSEPH, MISSOURI.

DESIGN FOR A STREET-LAMP.

No. 39,345.

Specification for Design.

Patented June 9, 1908.

Application filed March 19, 1908. Serial No. 422,189. Term of patent 3½ years.

To all whom it may concern:

Be it known that I, CHARLES P. MASSARD, a citizen of the United States, residing at St. Joseph, in the county of Buchanan and State of Missouri, have invented a new, original, and ornamental Design for Street-Lamps, of which the following is a specification; reference being had to the accompanying drawings, forming a part thereof.

The figure is an enlarged elevation of said street lamp.

I claim:

The ornamental design for a street lamp, as shown.

CHARLES P. MASSARD.
